United States Patent Office.

WILLIAM D. ROBINSON, OF BUFFALO, NEW YORK.

Letters Patent No. 94,242, dated August 31, 1869.

IMPROVEMENT IN SHIPS' FENDERS.

The Schedule referred to in these Letters Patent and making part of the same.

To all whom it may concern:

Be it known that I, WILLIAM D. ROBINSON, of Buffalo, in the county of Erie, and State of New York, have invented certain new and useful Improvements in "Fenders" for Vessels; and I do hereby declare that the following is a full and exact description thereof, reference being had to the accompanying drawings, making part of this specification, in which—

Figure 1 is a side elevation, and

Figure 2, an edge view, both showing the fender suspended.

Like letters of reference indicate corresponding parts in both figures.

My invention consists in providing a spring-fender, for use by vessels, steamers, canal-boats, &c., to be hereinafter fully described.

In the drawings—

A A' represent the two sides of the fender, preferably made of wood, of suitable length, thickness, and width, which are securely fastened together at the two ends, first, however, inserting blocks *a a'*, as clearly shown in fig. 2, and thus leaving a space, *b*, between the side pieces A A'.

The inner edge of the upper block *a* is made rounding, and slightly grooved, to admit the holding-rope B, by which the fender is suspended from the vessel's sides.

The object of forming these fenders as above described, is, to allow their springing when struck or pressed, and thus resist or lessen the shock when two vessels come together, or the boat comes to the pier or dock, or alongside another vessel, and thus prevent damage to either, as the fenders usually employed are

apt to break or to injure the boat, or the jar seriously damage the vessel, or the machinery, if a steamer.

By the use of my spring-fenders, the shock will be received on the flat side, which will force it into the space *b*, toward the other side, and when the strain is removed, it will at once spring back, and thus will obviate greatly, if not altogether, the disagreeable and damaging jar and concussion of a collision with either vessels or docks.

To further aid in producing this springy effect, and to prevent the side of the fender being forced in too far, I intend to employ, if found desirable, one or more pieces of rubber, or its equivalent, *c c c*, and place them tightly between the side pieces A A', as clearly shown in fig. 2.

The advantages of this construction are too plainly discernible to need enlarging on. Besides their great and unquestionable usefulness, and supplying a want long felt, they will be very light and cheap, and there will be little or no danger of their breaking.

What I claim as my invention, and desire to secure by Letters Patent, is—

The fender within described, consisting of side pieces A A' and end blocks *a a'*, with the longitudinal space *b* between the sides, the whole arranged and operating as herein set forth.

In witness whereof, I have hereunto signed my name, in the presence of two subscribing witnesses.

W. D. ROBINSON.
